UNITED STATES PATENT OFFICE.

GEORGE HILLER STEBBINS, OF LOUISVILLE, KENTUCKY, ASSIGNOR TO CONTINENTAL CAR COMPANY OF AMERICA, OF LOUISVILLE, KENTUCKY, A CORPORATION OF KENTUCKY.

DUMP CAR.

1,413,946.

Specification of Letters Patent. Patented Apr. 25, 1922.

Application filed April 15, 1921. Serial No. 461,596.

To all whom it may concern:

Be it known that I, GEORGE H. STEBBINS, a citizen of the United States, and a resident of Louisville, in the county of Jefferson 5 and State of Kentucky, have invented certain new and useful Improvements in Dump Cars, of which the following is a specification.

My invention relates to dump cars of the kind employed on railroads to transport coal, rock, sand and other material adapted to be discharged from the car by a dumping operation. The invention relates more particularly to the operating mechanism for cars 15 of this character, and has for its object to provide an operating mechanism of simple and strong construction, for which the motive force is compressed air under the control of valves located in the engine cab.

Referring to the accompanying drawings for a specific disclosure of an embodiment of the invention,

Figure 1 is a side elevation of a dump car having my invention applied thereto,

Figure 2 is a horizontal sectional view taken on a plane just above the operating cylinders,

Figure 3 is a central transverse vertical section,

Figure 4 is a view of a piston and rack forming part of the operating mechanism,

Figure 5 is a transverse section through the center sill showing details of the operating gearing, and

Figure 6 is a transverse vertical section illustrating a slight modification of the gear arrangement.

As shown by the drawings, the dump car to which my invention is adapted to be applied is of the type in which the car body is pivotally supported on a central longitudinal axis located well below the floor of said body. The numeral 2 designates the car body. Fixed to the under side of the floor 40 of said body is a series of plates having depending lugs 3 which are pivoted in the bifurcated ends of a corresponding series of standards 4, the latter being bolted to the center sill 5. These series of pivots, which 45 are located in a straight line, provide a pivotal support for the car about which it can be bodily rotated, by the mechanism hereinafter described, to an angle of substantially forty-five degrees.

Supported on the lower side of the car

floor, preferably midway the ends thereof is a toothed sector 6 having extensions 7 which are bolted to angle brackets 8 secured to the car floor, the sector being braced transversely by angle pieces 9 bolted thereto and to suitable angle brackets secured to the car floor. Geared with sector 6 is a bevel pinion 10, fixed to the upper end of a shaft 11, which is journaled in bearings 12 secured to the center sill, the sector operating between said pinion and an antifriction roller 13 carried by a bracket 14 on the car sill. Keyed to shaft 11, between the bearings thereof, is a spur gear 15 which projects laterally through slots cut in the webs of the two I-beams constituting the center sill. Bolted to the outer sides of the webs of said I-beams are a pair of cylinders 16, in which work pistons 17 and piston rods 18. The piston rods are extended and have formed on opposed sides thereof gear teeth 19 which mesh with spur gear 15, the said piston rods being guided and protected by housings 20 bolted to the I-beam webs.

For operating the mechanism described above, fluid pressure is admitted to one end of one cylinder 16 and to the opposite end of the other cylinder 16 from any suitable source, such as the main reservoir of the air brake system. The valve mechanism for 85 controlling the admission to and exhaust from the cylinders would probably be located in the engine cab so as to be under the control of the engineer. I have not illustrated any such connections and controlling means, 90 for the reason that they form no part of my invention, and it will be obvious to those skilled in the art how such connections and means could be constructed and arranged to produce the results herein stated. Assuming, then, that air under pressure is admitted to opposite ends of the two pistons respectively, it will be obvious that one piston will move forward and the other rearward, thus 95 producing rotation of spur gear 15 and consequent tilting of the car body 2 to one side or the other depending upon which ends of the cylinders are supplied with air. To return the car to horizontal position after the load has been discharged, the above enumerated steps are just reversed and when the car reaches its normal position it is held in such position and prevented from tilting the other way by the chains designated by reference character 21.

It will be understood by those skilled in the art that the usual fastening means used with this type of car are provided for holding the car in a normal horizontal position, it being necessary to release such holding means prior to setting the dumping mechanism in operation. Such means in the present instance are the chains 21.

Figure 6 illustrates a slight modification of the operating gear. The mechanism shown in this view is in all respects the same as that already described, except that the toothed sector extends below the car sill. The only modification rendered necessary by this change is an enlargement of the radius of the toothed sector and a reversal of the position of the bevel gear meshing therewith.

Having fully disclosed the structure and mode of operation of my invention, what I claim as new and desire to secure by Letters Patent is:

1. A dump car comprising a body portion and a center sill, said sill including two spaced vertical I-beams extending throughout the longitudinal extent of the car, a series of standards bolted to said sill, a body pivotally mounted on the upper ends of said standards, a toothed sector fixed to said body concentric with the pivotal axis thereof, a vertical shaft journaled in said sill and extending between the I-beams thereof, a bevel gear on the upper end of said shaft meshing with said toothed sector, a spur gear mounted on said shaft and projecting laterally through slots in the web portions of said I-beams, a cylinder bolted to each side of said center sill, a piston and a piston rod operating in each cylinder, said piston rods having extensions with gear teeth formed on the inner sides thereof, said teeth meshing with said spur gear, and an elongated housing for each of said piston rods bolted to the webs of said I-beams.

2. A dump car comprising a body portion and a center sill, a series of standards bolted to said sill, a car body pivotally mounted on the upper ends of said standards, a toothed sector depending from said body in a transverse plane and arranged concentric with the pivotal axis of said body, a vertical shaft journaled in said sill, a bevel gear on the upper end of said shaft meshing with said toothed sector, a spur gear mounted on said shaft, a cylinder bolted to each side of said center sill, a piston and a piston rod operating in each cylinder, the piston rods having extensions with gear teeth formed on the inner sides thereof, said teeth meshing with

said spur gear, and an elongated housing for each of said piston rods bolted to said center sill.

3. A dump car comprising a body portion pivoted to the center sill of the car about a horizontal longitudinal axis between the body portion and center sill, a toothed sector depending from said body portion in a transverse plane at right angles to said pivotal axis and arranged concentric with said pivotal axis, a vertical shaft journaled in said center sill, a bevel gear on the upper end of said shaft meshing with said toothed sector, a spur gear mounted on said shaft, a pair of pistons bolted to said center sill, a piston and a piston rod operating in each cylinder, the piston rods having extensions with gear teeth formed on the inner sides thereof, said teeth meshing with said spur gear.

4. A dump car comprising a body portion pivoted to the center sill about a horizontal longitudinal axis, a toothed sector depending from said body portion in a transverse plane and arranged concentric with said pivotal axis, a vertical shaft journaled in the center sill, a bevel gear on said shaft meshing with said toothed sector, a spur gear mounted on said shaft, a pair of pistons bolted to said center sill, a piston and a piston rod operating in each cylinder, the piston rods having extensions with gear teeth formed on the inner sides thereof, said teeth meshing with said spur gear.

5. A dump car comprising a body portion pivoted to the center sill about a longitudinal axis, a toothed sector depending from said body portion in a transverse plane and arranged concentric with said pivotal axis, a vertical shaft journaled on the center sill, a bevel gear on said shaft meshing with said toothed sector, and fluid pressure actuated means disposed parallel with said longitudinal axis for rotating said shaft in either direction.

6. A dump car of the kind described, comprising a body portion pivoted to the center sill about a longitudinal axis, a gear sector depending from said body portion in a transverse plane and arranged concentric with said pivotal axis, an antifriction lateral guide bearing for said sector; a longitudinally disposed cylinder fixed to the center sill and adapted to have fluid pressure admitted to and exhausted from the ends thereof, a piston and a piston rod operating in said cylinder and gear connections between said piston rod and said gear sector.

GEORGE HILLER STEBBINS.
